EX

No. 14,546

JAN 15, 1884

UNITED STATES PATENT OFFICE.

JOHN McLEAN, OF BROOKLYN, NEW YORK.

DESIGN FOR A GATE.

SPECIFICATION forming part of Design No. 14,546, dated January 15, 1884.

Application filed November 20, 1883. Term of patent 7 years.

To all whom it may concern:

Be it known that I, JOHN McLEAN, a resident of Brooklyn, in the county of Kings and State of New York, have invented and produced a new and original Design for a Gate, of which the following is a full description, in connection with the accompanying drawing, which represents a face view of my improved gate.

10 This invention relates to an ornamentation of a gate; and it consists in the novel grouping and configuration of the parts that constitute it.

15 The main outline of the gate is composed of a bottom bar, *a*, uprights *b b*, and a curved top, *d*. The bar *a* has downwardly-projecting

pointed ornaments *e e*, as shown. The space bounded by the parts *a*, *b b*, and *d* is filled by groups *f f* of conventional leaves and flowers, and by heart-shaped figures *g g*, as shown. 20 The upper ends of the uprights *b b* have crown-pieces *h*, and on top of the gate is an ornamental scroll, *i*.

I claim—

25 The design for a gate, the same consisting of the parts *a*, *b*, *d*, *f*, and *g*, substantially as shown.

JOHN McLEAN.
